CUTTING-OFF MACHINE

Herbert J. White, Wayne Township, Passaic
County, N. J.

Application December 19, 1935, Serial No. 55,265

9 Claims. (Cl. 51—278)

The present invention relates to cutting-off machines and processes and particularly to machines and methods in which abrasive cutting-off wheels are employed for cutting metal stock.

5 The primary object of this invention is to provide a faster cutting-off method than any heretofore devised.

A further object of the invention is to provide a cutting-off method which is characterized not only by high speed production but also by increased life of the cutting-off tool, especially where an abrasive wheel is employed as the tool.

Still another object of the invention is to provide a cutting-off machine which will be of simple and practical construction and which will operate according to the method of this invention.

Other objects of the invention will be apparent hereinafter from the specification and from the recital of the appended claims.

20 Cutting-off machines of the prior art employ rotary tools or reciprocating tools, such as circular saws, grinding wheels or reciprocating saws, and the cut is effected by feeding the tool transversely through the bar of stock. In these prior art machines, the area of contact between the tool and the work is large and it increases as the tool feeds toward the center of the bar. The rate of cutting, therefore, is necessarily slow. Moreover, because of the large area of contact between the tool and the work, wear of the tool is quite rapid. Grinding wheels especially have a relatively short life and their scope of use for this reason has been very much restricted.

25 The present invention is based upon an entirely new principle of cutting. Instead of cutting by simply feeding the tool transversely through the bar, the cut is effected by relatively revolving the tool around the bar as it feeds into the bar. Thus the blank is cut off the bar by an ever-deepening spiral cut. At all times, the area of contact between the tool and the bar is relatively small; the cutting operation may, therefore, be speeded up and yet the life of the tool is increased. The present invention makes it practical to use a grinding wheel in cutting-off all sizes of metal stock.

30 The process of the present invention and a preferred form of machine for practicing the invention are illustrated more or less diagrammatically in the accompanying drawings. In the machine shown, a pair of grinding wheels are employed as the cutting-off tools. The two wheels are mounted to operate simultaneously at diametrically opposite points on the work. They are rotated upon their respective axes and simul-

taneously revolved together about the bar and fed into the bar. Thus they take a continual deepening spiral cut into the bar. When the bar has been cut to such depth that the two wheels approach very close to one another, one wheel is withdrawn and the other wheel continues to feed into the bar until it has completely severed the blank from the bar. In the machine shown, the revolutionary movement of the wheels about the bar of stock, effects a slow feed movement 10 of the wheels into the bar through a linkage and a set of differential gears.

In the drawings:

Fig. 1 is a front elevation of the machine described, illustrating the position of the cutting wheels and the bar of stock just prior to the beginning of the cut;

Fig. 2 is a similar view, but showing the position of the wheels when the blank is partly severed from the bar;

Fig. 3 is a view similar to the Figs. 1 and 2 and showing the positions of the wheels immediately after the blank has been severed from the bar;

Fig. 4 is a side elevation with some parts broken away, of the machine shown in Figs. 1 to 3;

Fig. 5 is a fragmentary view on an enlarged scale, showing a detail of the feed mechanism for one of the cutting wheels;

Fig. 6 is a view illustrating diagrammatically the extent to which the two wheels may be fed 30 toward one another before one is withdrawn;

Fig. 7 is a view illustrating diagrammatically the principle of cutting of the present invention; and

Fig. 8 is a view illustrating diagrammatically 35 by way of contrast the principle of the cutting-off methods practiced prior to the present invention.

Referring now to the drawings by numerals of reference, 10 indicates the main base of the cutting-off machine shown. Upon this main base at either side thereof are provided a pair of supporting arms 11 and secured to the base between these arms is a bracket 12. Each of the arms 11 carries a roller 13 and the bracket 12 carries 45 a roller 14. These rollers will preferably be ball- or roller-bearing mounted upon their respective supporting arms or bracket. The rollers 13 and 14 are so disposed relative to one another as to provide a three-point support for a cylindrical 50 carrier plate 15.

The plate 15 carries the grinding wheels or other cutting-off tools. There are a pair of studs 20 and 21 secured in the plate 15 and upon these studs are pivotally mounted the lever arms 22 and 55

23, respectively. There is a motor 24 secured by screws 26 to the free end of the lever arm 22 and there is a motor 27 secured by screws (not shown) to the free end of the lever arm 23. The armature shafts 28 and 29, respectively, of these motors project forwardly through arcuate slots 30 and 31, respectively, formed in the carrier plate 15 and upon the forward ends of these shafts are secured the grinding wheels 34 and 35.

10 The carrier plate 15 is formed with a central opening and it is mounted upon and secured to a sleeve 37 which extends forwardly through this opening. The base 10 of the machine is formed at its rear with an upright or arm 42 that is provided at its upper end with a bearing or support 43 for the rear end of the sleeve 37. The carrier plate 15 is secured to the sleeve 37 by screws 38 (Fig. 4).

20 The bar of stock from which blanks are to be cut off is designated as B. It is fed through a feed-tube denoted at 40. The feed-tube is mounted in the sleeve 37.

25 Rotatably mounted upon the sleeve 37 is a second sleeve 45. Arms 60 and 61, which are integral with the sleeve 45 extend from diametrically opposite points of the sleeve.

30 The arm 60 is connected by a pin 62 to a link 68 which, in turn, is connected by a pin 65 to the lever arm 22. The other arm 61 is connected by pin 67 to link 68. There is a bayonet slot 69 formed in the free end of this latter link. This slot is adapted to receive a pin 70 that is mounted in the lever arm 23 and the lever arm 23 is formed with a transverse slot 73 through which 35 the link 68 may move relative to the arm.

35 The pin 70 is adapted to rest upon a nose or projection 74 formed upon the link 68 and defining the bayonet slot 69. The link 68 is normally pressed in a counter-clockwise direction 40 about its pivot 67 by a spring-pressed plunger 75. This plunger serves to hold the link normally in such position that the nose 74 engages under the pin 70.

45 The plunger 75 is mounted in an opening or recess 76 formed in a lug 77 which is integral with the lever arm 23. The plunger is actuated by the coil-spring 78 housed in this opening or recess. The plunger carries a roller 80 that engages and rides on one side surface of the link 50 68. Nuts 81, which are threaded on the stem of the plunger, serve to limit its rightward movement.

55 The link 68 is formed on the side opposite that engaged by the roller 80 with a cam-projection 83. This cam-projection has an inclined or beveled surface 84 at one end. There is a pin 85 secured in the carrier-plate 15. This pin is adapted to ride up on the bevel 84 of the cam-projection 83 as the cutting wheels feed into 60 depth and it disengages the link 68 from the pin 70, allowing the wheel 35 to drop back away from the work to avoid interference with its companion wheel 34 when the cut has proceeded so far that the wheels approach one another.

65 The feed of the wheels into the work is produced by the relative rotation between the carrier plate 15 and the sleeve 45 as will now be described.

70 Fastened to the sleeve 37, as by means of the set-screw 50 is a spur gear 51. Fastened to or integral with the sleeve 45 is a spur gear 52. These two spur gears have different numbers of teeth. The difference in number of their teeth 75 will depend upon the fineness of the feed desired.

For extremely slow feed, one gear would have one less tooth than the other.

75 The two gears 51 and 52 mesh with a single wide-faced pinion 54. This pinion is rotatably mounted upon a stud 53 that is secured in a bracket 56 which is integral with or fastened in any desired manner to the arm 42.

The arm 56 extends through an opening 57 in a hood or cover that encloses the parts of the machine and is secured to the carrier plate 15 10 by screws 59.

15 The carrier-plate 15 may be revolved by any suitable means (not shown).

The operation of the machine will now be described.

15 Assuming that the parts are in the positions shown in Figs. 1 and 4 with the wheels 34 and 35 in withdrawn position and with the bar B projecting forward from the tube 40 a distance determined by the length of the piece of stock 20 to be cut off the bar and with the pin 70 resting on the nose 74 of link 68, the machine is ready for operation. The machine is put into operation by starting the motors 24 and 27, which drive the grinding wheels 34 and 35, and by applying power 25 to the carrier-plate 15 to revolve this plate about its axis.

30 As the carrier-plate revolves, it carries the rotating grinding wheels 34 and 35 about the bar B and simultaneously rotates the sleeve 45 to cause the grinding wheels to be fed into the bar. The drive to the sleeve 45 is from the carrier-plate through the sleeve 37, which is secured to the carrier-plate, the gear 51, which is fastened to this sleeve, the pinion 54, which meshes with 35 this gear, and the gear 52 which meshes with the pinion 54 and is integral with the sleeve 45. The gears 51 and 52 will be chosen as described to have but slightly different numbers of teeth. Hence, the differential gearing 51—54—52 will 40 drive the sleeve 45 at a much slower rate than the rate of rotation of plate 15 and the plate 15 will make many revolutions while the sleeve 45 is rotating through a slight angle.

45 The sleeve 45 is connected with the lever 22 by arm 60 and link 68 and it is connected with the lever 23 by arm 61, link 68, nose 74 and pin 70. Hence, when rotational movement in one direction is imparted to the sleeve 45, the grinding wheels 34 and 35 are rocked about their 50 pivots 20 and 21 to feed into the bar B.

55 Fig. 1 shows the beginning of the operation. Fig. 2 shows the positions of the wheels after the plate 15 has made a number of revolutions and the sleeve 45 has been rotated by the differential through a large enough angle to have caused the grinding wheels to approach very close to one another. At this stage, the bar B will have been cut through by the revolution and feed of the wheels to a point where the stock left 60 to be cut through has been reduced to the diameter indicated by the circle 92 in Figs. 2 and 6. The link 68 will have been moved to a point where the pin 85 begins to ride up on the cam-projection 83 of link 68.

65 This will cause the link 68 to be rocked about its pivot 61, compressing the plunger 75. In the further revolution of the plate 15 and rotation of the sleeve 45, the pin 85 will ride up on the projection 83 and the nose 74 of link 68 will be disengaged from pin 70. The lever 23 will then drop back to the position shown in Fig. 3, withdrawing the wheel 35 from the cut. The wheel 34 remains in the cut, however, and in the continued rotation of carrier-plate 15 and sleeve 75

45 will be fed down into the bar B until, as shown in Fig. 3, it passes completely through the bar, severing the blank from the bar.

Then the rotation of the carrier-plate 16 may be reversed to withdraw the wheel 34 and rotate the parts back to the position shown in Fig. 1. When the link 68 has been moved back to such position, the plunger again causes the nose 74 of link 68 to engage under pin 76 so that the parts 10 are again ready for operation. When the wheels have been withdrawn, the bar may be fed forward in the tube 40 to present another length of stock to be cut. This feeding mechanism has not been illustrated but may be of any suitable type of 15 which many are well known in the art. When the bar has been fed forward, a new piece may be cut from the bar as before.

It is desirable to adjust the distance between the wheels 34 and 35, when in withdrawn position, 20 to conform to the diameter of the bar of stock to be cut. To effect adjustment of the distance between the wheels, the gear 51 may be rotated by rotation of the worm 90 (Fig. 4). This worm meshes with a wormwheel 91 that is integral with 25 the gear 51. The worm is mounted to revolve with the wormwheel during operation of the machine and may be rotated for adjustment by inserting a wrench through opening 57 in guard 58. The shaft 96 of the worm may be suitably shaped to 30 be manipulable by the wrench.

As will be apparent, in the operation of cutting off a blank from a bar of stock, each grinding wheel will, as shown in Fig. 7 take a depthwise cut into the bar. Here one wheel is indicated at W 35 and the spiral path of the wheel in the cutting operation is denoted by the numerals 95. It is evident from this figure that the area of contact between the wheel and the bar is relatively small at all times. Hence, the spiral cutting-off movement can be performed very rapidly. Moreover, 40 wear on the wheel will be a minimum.

The present method of cutting is to be contrasted with the method of the prior art which is illustrated in Fig. 8. In the prior art method, the 45 wheel, indicated at W' cuts by simply being fed transversely through the bar B'. It is obvious that there is a much larger area of contact between the wheel and the bar with this type of feed than with the spiral feed of the present invention 50 and that the old process is much slower and wear on the wheel is much greater.

While the invention has been described in connection with a machine in which the tool is revolved about and simultaneously fed into the 55 work to effect the cutting-off action, it will be obvious that instead, the work might be rotated on its axis while being fed into the tool. Many other modifications of the invention will occur to those skilled in the art. Thus, for instance, when 60 one wheel is withdrawn after the blank has been partly severed from the bar, the spiral feed of the other wheel may be discontinued and the cut completed by simply feeding this other wheel transversely through the remainder of the bar. 65 The diameter of the remaining non-severed portion of the bar will be sufficiently small so that the area of contact between wheel and bar will not be great and the wheel can be fed on transversely through the bar rapidly and without any appreciable wear.

Still other modifications of the invention will occur to those skilled in the art. This application is intended to cover all modifications, variations 75 or uses of the invention coming within the scope

of the invention and the limits of the appended claims.

Having thus described my invention, what I claim is:

1. The method of cutting a blank from a bar of stock in which a pair of rotary cutting tools are employed and the rotating tools are revolved about the bar while being fed into the bar until the bar has been cut through to a predetermined depth, and then one of the tools is withdrawn and the other tool completes the cut. 6

2. The method of cutting a blank from a bar of stock in which a pair of rotary cutting tools are employed and the rotating tools are revolved about the bar while being fed into the bar until the bar has been cut through to a predetermined depth, and then one of the tools is withdrawn and the other tool is fed transversely directly through the bar to complete the cut. 15

3. A cut-off machine comprising a work support for holding a bar of stock, a rotary disc cutting tool, a carrier upon which the cutting tool is mounted, means for revolving the carrier to produce a rotational movement of the tool about the center of the work and means operatively connected to the carrier and operated by the carrier in its rotation for simultaneously producing a continuous relative depthwise feed movement between the tool and the work radial of the center of the work to sever a piece from the bar. 20 30

4. A cut-off machine comprising a work support, a rotatable carrier, a tool support movably mounted on said carrier, a cutting tool mounted on said tool support, means for rotating the carrier to move the tool about the work, and means comprising a differential for effecting movement of the tool support on the carrier as the carrier rotates. 35

5. A cut-off machine comprising a work support, a rotatable carrier, a tool support movably mounted on said carrier, a cutting tool mounted on said tool support, a rotary actuating member, means operatively connecting the actuating member to the tool support to move the tool support on rotation of the actuating member, means for 45 rotating the carrier, and a differential operatively connecting the carrier and the actuating member to rotate the actuating member on rotation of the carrier but at a different rate. 50

6. A cut-off machine comprising a feed tube for supporting the work, a rotatable carrier having a central opening concentric of said tube and through which the work may be fed, a tool support movably mounted on said carrier at one side of the feed opening for movement toward and from the center of said opening, an actuating member, a differential operatively connecting the carrier with the actuating member to operate the actuating member on rotation of the carrier. 55 60 means operatively connecting the actuating member to the tool support to operate the tool support on actuation of said member, and means for rotating the carrier.

7. A cut-off machine comprising a feed tube to support the work, a rotatable carrier having a central opening concentric of said tube and through which the work may be fed longitudinally, a pair of cutting tools movably mounted on the carrier at opposite sides of said opening, means 70 for rotating the carrier, means for moving said cutting tools simultaneously on the carrier toward said opening to effect feed movement of the tools into the work, and means for discontinuing the last named movement of one of the cutting tools 75

when the cut has proceeded to a predetermined depth.

8. A cut-off machine comprising a work support, a tool support, a pair of rotary cutting-off tools mounted on said tool support at opposite sides of the work, means for rotating the tools, means for producing relative rotational movement between said supports about the center of the work, means for simultaneously feeding said tools depthwise into the work carried by said work support, and means for discontinuing the feed movement of one tool when the cut has progressed to a predetermined depth.

9. A cut-off machine comprising a feed tube for supporting a bar of stock, a sleeve journaled on said tube, a rotatable carrier having a central opening therein and journaled coaxially of said tube and sleeve, a tool support pivotally mounted on said carrier for movement toward and from the work, a linkage pivotally connecting the tool support to the sleeve, differential mechanism connecting the sleeve and carrier, and means for rotating the carrier to revolve the tool support about the work and simultaneously effect pivotal movement of the tool support.

HERBERT J. WHITE.
